Primary Examiner — Kevin K Rudzinski*Assistant Examiner* — Clare Ann Gannon(74) *Attorney, Agent, or Firm* — Fox Rothschild LLP(57) **CLAIM**

The ornamental design for a garment, as shown and described.

DESCRIPTION

FIG. 1 is a front view of a garment according to the new design; and,

FIG. 2 is a rear view thereof.

The broken lines depict portions of the article that form no part of the claimed design.
